DESIGN FOR A WAFFLE IRON

John A. Salvia, Rochester, N. Y., assignor to Samson-United Corporation, Rochester, N. Y.

Application February 19, 1935, Serial No. 55,495

Term of patent 7 years

To all whom it may concern:

Be it known that I, John A. Salvia, a citizen of the United States, residing at Rochester, in the county of Monroe and State of New York, have invented a new, original, and ornamental Design for Waffle Irons, of which the following is a specification, reference being had to the accompanying drawing, forming a part thereof.

The figure is a perspective view of the waffle iron.

The dominant feature of this design resides in the part shown in full lines.

I claim:

The ornamental design for a waffle iron, as shown and described.
